DISPENSING DEVICE

Harold C. Bowman, Rocky River, Ohio

Application September 10, 1938, Serial No. 229,336

4 Claims. (Cl. 221—116)

This invention relates to dispensing devices, and more particularly to apparatus for dispensing finely divided or comminuted solid materials, as those in a granulated or pulverized state.

5 An object of the invention is to provide an improved dispensing apparatus which will be simple in construction and operation.

Another object of the invention is to provide an improved dispensing apparatus which will be composed of few and easily manufactured parts.

10 Another object of the invention is to provide an improved dispensing apparatus which may be easily assembled.

Another object of the invention is to provide an improved dispensing apparatus which may be readily and economically manufactured.

Another object of the invention is to provide an improved dispensing apparatus which may be easily kept clean and sanitary.

20 Another object of the invention is to provide an improved dispensing apparatus which will be efficient in operation.

Another object of the invention is to provide an improved dispensing apparatus which will dispense pre-determined quantities of material.

25 Another object of the invention is to provide an improved dispensing apparatus which will prevent clogging by materials which tend to pack together.

30 Another object of the invention is to provide an improved dispensing apparatus which will occupy little space.

Another object of the invention is to provide an improved dispensing apparatus which will be neat and attractive in appearance.

35 Other objects will hereinafter appear.

The invention will be better understood from the description of two practical embodiments thereof illustrated in the accompanying drawings in which:

40 Figure 1 is a perspective view of an embodiment of the invention particularly adapted to dispense materials composed of relatively large particles, such, for instance, as ground coffee, granulated sugar, and the like;

45 Figure 2 is a central sectional view of the device of Figure 1 taken on the line II—II thereof;

Figure 3 is a perspective view of a second embodiment adapted for use with more finely divided materials as powdered sugar and malted milk, and

50 Figure 4 is a central sectional view taken on the line IV—IV of Figure 3.

In the embodiment shown in Figures 1 and 2, the device is illustrated as consisting of a sup-

porting bracket, by which is carried the measuring and ejecting mechanism of the device, and also a reservoir or magazine in which the material to be dispensed is retained, this magazine being shown as a generally cylindrical container immediately above the measuring part of the apparatus so that the material may be easily fed by gravity.

5 The bracket illustrated consists of a generally channel-shaped metallic piece having a vertical web 1 by which it may be secured to any supporting element, such as a wall or a portion of a cupboard or the like, and upper and lower horizontal flanges 2 and 3 by which it is attached to the measuring and discharging part of the apparatus.

10 The attachment is illustrated as by headed studs 4 secured to the measuring mechanism and passing through key hole slots 5 in flanges 2 and 3.

The measuring and dispensing apparatus is contained within a covering, casing or frame comprising a depending frustro conical funnel-like outlet portion 6 and an upwardly extending cylindrical flange 7, by which the mechanism is retained and which supports the reservoir.

15 The reservoir is shown as a cylinder 8, preferably of transparent material, such as glass or molded plastic material, closed at its top by a cap 9.

20 The measuring apparatus consists of two movable discs 10 and 11 mounted horizontally and spaced apart to accommodate a stationary charge receiving and measuring disc 12. The movable discs are each provided with a number of apertures 13, shown as three, those of the upper disc being placed out of alignment with those in the lower, while the charge measuring disc is provided double the number of spaces 14 so that one-half these apertures may be in register with the openings of one of the movable discs and the other half in register with those of the other.

25 The discs 10 and 11 are shown as mounted on a hexagonal shaft to which is secured an actuating lever 16, passing laterally out through a slot 17 in the conical part of the frame and terminating in a handle 18 by which it may be actuated, these being held together by a bolt 19 and nut 20 and maintained in properly spaced relation by a tube 21 and washers 22.

30 Overlying the upper disc 10 is a scraping element or anti-clogging device shown in the first two figures as a sheet metal spider 23 having an upwardly extending central boss 24 and three outwardly extending arms which scrape the material being dispensed into the openings in the

charge receiving disc as the apertures of disc 10 are brought into alignment therewith.

As most of the weight of the material is carried by disc 10, there is, until the reservoir is emptied, always a substantial amount of material in position to be scraped into openings 14.

It will be apparent that whenever the handle is oscillated from its foremost to its rearmost position, or vice versa, disc 10 uncovers three openings 14 which are filled as they are uncovered, and simultaneously covers three previously filled openings 14. At the same time, disc 11 closes the bottoms of the first mentioned three openings, so that they will retain the charge being delivered to them, and opens the three second mentioned openings, permitting their contents to drop through the funnel-like frame bottom into a receptacle which may be placed thereunder.

Hence, a given quantity by volume is discharged 20 every time the handle is oscillated from front to rear position, or vice versa.

The embodiment of the invention above described is particularly suitable for kitchen use, as previously indicated, for coffee and similar 25 ground or granular materials.

The device illustrated in Figures 3 and 4 resembles closely that of the first two figures, excepting that certain changes have been indicated in the anti-clogging device and in the reservoir.

The reservoir 108 is shown as of glass or similar material being formed in a cylinder having a closed end 109 adapted to be positioned at the top and having a thread 107a for securing it to 35 the threaded flange 107 of the measuring and dispensing apparatus.

In this instance, the anti-clogging device is shown as made of a plurality of strips 123, set on edge and secured as by riveting, welding, brazing, 40 or the like. This type of scraper is found to operate particularly well with powdered material, the particles of which are inclined to pack and stick together if given any substantial stationary base upon which to rest.

45 The parts of the dispensing mechanism can all be easily produced, as of sheet metal stampings, screw machine products, or molded fiber.

While I have described the illustrated embodiments of my invention in some particularity, obviously many others will readily occur to those skilled in this art, and I do not, therefore, limit myself to the precise details shown and described, but claim as my invention all embodiments, variations, and modifications thereof coming within the scope of the appended claims.

55 I claim:

1. A dispensing device comprising a reservoir, a movable bottom disc therefor adapted to support the weight of the contents of the reservoir, 60 means for oscillating the disc, the disc being provided with an aperture, a stationary member

below the disc having a material receiving space with which the aperture of the disc is adapted to be brought into alignment, and a second disc rotatable with the first disc, beneath the stationary member and having an aperture out of alignment 5 with the aperture of the first disc, and adapted to be brought into alignment with the space of the stationary member, and a stationary scraper overlying the first mentioned disc.

2. A dispensing device comprising a reservoir, 10 a movable bottom disc therefor adapted to support the weight of the contents of the reservoir, means for oscillating the disc, the disc being provided with an aperture, a stationary member below the disc having a material receiving 15 space with which the aperture of the disc is adapted to be brought into alignment, and a second disc rotatable with the first disc, beneath the stationary member and having an aperture out of alignment with the aperture of the first disc, and adapted to be brought into alignment with the space of the stationary member, and a stationary scraper comprising a narrow upwardly extending baffle overlying the first mentioned disc.

25 3. A dispensing device comprising a reservoir, a movable bottom disc therefor adapted to support the weight of the contents of the reservoir, means for oscillating the disc, the disc being provided with a series of apertures, a stationary 30 member below the disc having a plurality of material receiving spaces, there being twice as many spaces as apertures in the disc with which the apertures of the disc are adapted to be brought into alignment, and a second disc rotatable with 35 the first disc, beneath the stationary member and having a series of apertures out of alignment with the series of apertures of the first disc, and adapted to be brought into alignment with the spaces of the stationary member, and a stationary scraper overlying the first mentioned disc and having a plurality of arms extending 40 radially between said apertures.

4. A dispensing device comprising a reservoir, 45 a movable bottom disc therefor adapted to support the weight of the contents of the reservoir, means for oscillating the disc, the disc being provided with an aperture, a stationary member below the disc having a material receiving space with which the aperture of the disc is adapted to be brought into alignment, and a second disc rotatable with the first disc, beneath the stationary member and having an aperture out of alignment 50 with the aperture of the first disc, and adapted to be brought into alignment with the space of the stationary member, and a stationary scraper overlying the first mentioned disc, and a converging outlet beneath said measuring 55 apparatus.

HAROLD C. BOWMAN. 60
